VALVE OPERATING MECHANISM FOR
ENGINES

Joseph D. Turlay, Flint, Mich., assignor to General Motors Corporation, Detroit, Mich., a corporation of Delaware

Application September 24, 1936, Serial No. 102,328

3 Claims. (Cl. 123—90)

This invention relates to a method of and means for controlling the valve lash or clearance in an internal combustion engine.

In the operation of an internal combustion engine the problem of controlling valve lash or clearance is a complicated one. If the valve lash is adjusted for normal conditions of operation there will be an excessive clearance when starting cold. This excess clearance results in unpleasant noise and tends to cause excessive wear of the several parts due to the pounding action thereof.

On the other hand if the clearance is reduced there may be insufficient clearance at more extreme operating conditions so that the valves will remain partially open and cause faulty operation and burning and/or pitting of the valves and the seats therefor.

To obtain satisfactory engine performance as quickly as possible after starting cold it is customary to provide a thermostat which remains closed until operating temperature is reached and forces the cooling medium, such as water for example, to recirculate through a bypass valve without passing through the radiator. The cooling medium usually surrounds the combustion chamber and cylinder wall and is rapidly heated to operating temperature even in the coldest weather from heat rejected from the engine.

The engine lubricant, however, is heated much more slowly. The lubricant is carried in the bottom of the engine away from the combustion zone. Relatively small quantities thereof are allowed to come in contact with the pistons and cylinder walls. Hence, the time required for the lubricant to reach even the normal water temperature is several times greater than the water itself. Under hard driving conditions or in warm weather the oil normally reaches a much higher operating temperature than the water.

The result of these two dissimilar temperature characteristics has a definite effect on valve lash or clearance and consequently upon valve mechanism noise. It is obvious that in order to maintain a constant valve lash with a change in temperature all units must expand or contract at an equal rate.

Consider the case of a simple correctly lashed valve mechanism when the engine is started cold. The upper portion of the engine quickly warms up and expands which means that the distance between the rocker arm shaft and the cam shaft increases. The push rods are insulated from the cylinder block and thus do not respond rapidly to changes in block temperature. In addition, the push rods receive a constant flow of oil and hence

their expansion will be a function of lubricant temperature. As was stated previously, the oil temperature rise is considerably slower than the water temperature rise which means that the distance between the cam shaft and rocker arm shaft is rapidly increased due to the expansion of the cylinder block. The push rod on the other hand receives a bath of cold oil from the crankcase and its temperature rise lags behind that of the upper part of the engine. Under this condition the push rod is too short and there is an excess of valve lash with resultant noise.

Under extreme driving conditions or in warm weather the antithesis of this situation will exist. The oil temperature will rise above that of the water. While the distance between the cam shaft and the rocker arm shaft will be increased as compared with the distance when the engine is cold the push rod will be expanded a greater amount and the push rods will become too long and reduce the lash.

The problem of valve lash is further complicated by another factor, namely, the unequal coefficients of expansion of cast iron and steel. Steel expands about 13% more per degree rise in temperature than does cast iron. It is customary to lash valves with the oil and water temperatures equal to the normal temperature of the water. The push rods being of steel contract more upon cooling than does the cylinder block of cast iron and therefore increases the valve lash several thousandths of an inch in cold weather. The cumulative effect of the several factors produces excessive noise in the valve mechanism during the warm up period. Various compensating means have been used in the past, usually of a complicated nature. I have devised a simple means for more effectively controlling valve lash than devices used in the past.

It is an object of my invention to improve the valve lash characteristics of an engine.

Another object of my invention is to provide a new and improved method and means for controlling the valve lash in an internal combustion engine.

A still further object of my invention is a new and improved method and means for maintaining more nearly constant than devices used in the past the valve lash or clearance of an internal combustion engine throughout widely variable conditions of operation.

It is also an object of my invention to provide valve mechanism in which noise is greatly reduced.

A specific object of my invention resides in a

new and improved rocker arm shaft support formed of aluminum or alloys thereof.

Another object of my invention is a new method and means of controlling valve lash involving regulation and control of the temperature of the lubricant for the push rod and expansion and contraction of rocker arm supports of different material than the engine block and push rods.

Other advantages and objects of my invention reside in the specific combinations and arrangements of parts as will become more apparent as the description proceeds.

Reference is herein made to the drawing forming a portion of this specification, in which:

Figure 1 is a side elevational view, with parts in section, of an internal combustion engine in which my invention is incorporated.

Figure 2 is a view taken substantially on line 2-2 in Figure 1; and

Figure 3 is an enlarged detail view taken on line 3-3 in Figure 1.

In the drawing, 1 is a piston adapted to reciprocate in cylinder 3. Spaced walls 2 and 4 form a passage 5 for cooling water or other medium to surround and cool piston 1. Cylinder head member 6, having passages 7, 8 and 9 for cooling water or other cooling medium, is adapted to form with the cylinder 3 a combustion chamber 10.

Valve 11 having a spring 12 between a support 13 on the cylinder head and a disc-like member 14 fixed to the upper end of the valve stem is adapted to close the valve against seat 15. By means of camshaft 16 having cam 17 thereon, cam follower 18, push rod 19, and rocker arm 20 the valve is caused to open against the force of spring 12 at timed intervals in the cycle of operation as will be readily understood.

A hollow rocker arm shaft 21 is supported from the upper face of the cylinder head by means of supports 22 formed of aluminum or alloys thereof. The supports 22 are fixed to the head by means of members 30. Preferably the supports are of aluminum alloy die castings in place of the malleable iron or ferrous metal supports commonly employed. The coefficient of expansion of aluminum is more than twice that of cast iron and this property is utilized for controlling the valve lash as will later become apparent.

Within and spaced from the inner walls of the shaft 21 is a tubular member 23 within which the cooling medium is caused to circulate by means of pump 24. Lubricating oil is forced by means of pump 25, pipe line 26 into space 27 between tube 23 and the inside of shaft 21. As shown in Figure 1, oil is forced into the space 27 at a point substantially midway between the ends of the rocker arm shaft. The oil will flow toward both ends of the rocker arm shaft and lubricate the several rocker arm bearings and push rods, oil passageway 28 permitting oil to reach the push rods. The water within tubular member 23 will regulate the oil temperature by heating a portion of the oil during the warming up period and cooling a portion thereof during extreme operating conditions. It will be understood that there may be any desired number of cylinders, pistons, valves, valve rocker arms and push rods.

By means of the construction described above the valve lash may be held within narrow limits. If now the engine be lashed as previously described with the oil and water temperatures equal to the normal water temperature the aluminum brackets will have expanded considerably in length from that of the cold condition thereof.

Upon a cooling of the several parts as by standing over night the brackets will contract approximately twice as much as would the same elements if formed of ferrous metal. Accordingly the contraction of the aluminum or aluminum alloy rocker arm support will be approximately twice as much or more than the ferrous metals used for the push rod or cylinder block and thereby decrease the valve stem clearance several thousandths of an inch under that of normal hot lash. Now since this is so, a certain amount of expansion of the cylinder block due to quick water temperature rise during "warm up" is possible before the lash reaches even its nominal value.

The temperature of the rocker arm supports is controlled in part by the water and in part by the oil flowing through the rocker arm shaft. The combined effect is something of a mean between the expansion expected if either factor predominated. However, their action is such that the maximum lash encountered during the warming up period is considerably under that obtained with malleable iron or other ferrous metal supports, thus appreciably reducing noise and wear of the several parts.

In the case of very hot oil under extreme operating conditions the aluminum or aluminum alloy supports expand greatly and maintain sufficient clearance by compensating for the increase in length of the steel push rods and valve stems.

Under extreme conditions of operation the portion of the hot oil which flows in contact with tubular member 23 containing the cooling medium will be cooled. The cooled portion flows to the push rods and they will remain cooler than would otherwise be the case.

It will be apparent that I have provided a simple and convenient means for controlling valve lash and valve mechanism noise.

Although I have shown and described one specific construction, form and arrangement of parts as illustrative of an embodiment of my invention, various changes may be made therein without departing from the spirit of my invention and I do not wish to limit the patent granted thereon other than as necessitated by the prior art.

I claim:

1. Mechanism for controlling valve lash in an internal combustion engine which comprises, a valve rocker arm, a rocker arm shaft, a push rod, means for maintaining the push rod cooler than the normal cooling medium temperature during the warming up period and hotter than the cooling medium under severe conditions of operation and means for supporting said rocker arm shaft, said last mentioned means constituting the sole supporting means for said shaft and being formed wholly of a material having a substantially greater coefficient of expansion than the other parts.

2. Mechanism for controlling valve lash in an internal combustion engine which comprises, a valve, a valve rocker arm, a valve rocker arm shaft, a push rod for operating the valve rocker arm, means for maintaining the push rod cooler than the normal cooling medium temperature during the warming up period and hotter than the cooling medium under severe conditions of operation and supporting means for the rocker arm shaft, said last mentioned means constituting the sole supporting means for said shaft and being formed wholly of material having a substantially greater coefficient of expansion than the other parts whereby the valve lash when the parts are cold is less than the normal hot lash.

and whereby the lash under severe conditions of operation is at least equal to normal hot lash.

3. An engine comprising a cylinder having a head, a piston in the cylinder, a valve in the head, operating means for the valve comprising a rocker arm shaft support mounted on the head, a rocker arm shaft mounted in the support, a rocker mounted on the shaft having one end engaging the valve, a push rod engaging the other end of the rocker, and means for operating the push rod to operate the valve, said engine being provided with the usual cooling system and lubricating

system, and said rocker arm shaft having passages therein, and means for circulating cooling fluid and lubricating oil from said systems through said passages to stabilize the temperature of the shaft and associated parts under different operating conditions, said shaft support being made wholly of material having a higher coefficient of expansion than the remainder of the valve operating means to maintain the valve lash substantially constant throughout the operating range. 10
